UNITED STATES PATENT OFFICE.

JOHN WILLIAM RYAN, OF SPRINGFIELD, ILLINOIS.

TIE.

1,390,928.

Specification of Letters Patent. Patented Sept. 13, 1921.

Application filed February 21, 1921. Serial No. 446,621.

To all whom it may concern:

Be it known that I, JOHN W. RYAN, a citizen of the United States, residing at Springfield, in the county of Sangamon and

5 State of Illinois, have invented new and useful Improvements in Ties, of which the following is a specification.

My present invention has reference to a combined tie and clamp for railway rails.

10 My primary object is to produce a combined tie and clamp for railway rails which is wholly constructed of metal, which will effectively engage the rails and which will also engage with the road bed in a manner 15 to prevent the lateral or longitudinal movement of the tie, and consequently similar movement of the rails.

It is a further object of the invention to produce a combined tie and clamp for railway 20 rails constructed of two similar metal members, each having its ends provided with rail engaging hooks, said members being disposed one over the other, and when so arranged the lips of one of the members are 25 arranged opposite the lips of the other member in rail receiving relation, each of said members, intermediate of its lips being twisted to provide angularly disposed contacting portions, the lower edges of which 30 being embedded in the road bed, and the construction being such that the contacting engagement of the said portions of the members will hold both of the members from lateral, longitudinal or sinking movement after the said members have been 35 connected.

It is a further object to produce a combined metallic tie and rail clamp which constitutes two similar members of a shape and 40 construction to permit of the ready association and connection of the members, and wherein the intermediate portions of the members have their lower edges embedded in the road bed and their sides engaged by 45 the road bed so that the longitudinal, lateral or sinking movement of the tie or rails will be effectively prevented.

It is a still further object to produce a combined railway tie and clamp which may 50 be employed with particular efficiency in mines.

The foregoing, and other objects which will appear as the nature of the invention is better understood, may be accomplished 55 by a construction, combination and opera-

tive arrangement of parts, such as is disclosed by the drawings which accompany and which form part of this application.

In the drawings:

Figure 1 is a plan view of a portion of a 60 railway having rails supported and connected in accordance with this invention.

Fig. 2 is a sectional view on the line 2—2 of Fig. 1, on an enlarged scale.

Fig. 3 is a perspective view of the com- 65 bined tie and clamp.

Fig. 4 is a similar view of one of the mem- bers of the tie.

Fig. 5 is a sectional view through a tun- 70 nel showing the manner in which the ties support rails on the bed thereof.

Fig. 6 is a sectional view on the line 6—6 of Fig. 5.

Fig. 7 is a plan view of a modified form 75 of one section of one of the ties which may be employed.

Referring now to the drawings in detail, the numeral 1 designates the rails of a track. These rails are supported and held in proper spaced relation to each other by ties con- 80 structed in accordance with this invention.

My improvement contemplates the em- 85 ployment of two similar members. This, in itself, is an important feature as the cost of production will be materially decreased.

Each of the members is formed from a flat sheet of metal, of sufficient strength and resiliency to withstand the strain to which they are subjected. Each member has one of its ends enlarged as indicated by the nu- 90 meral 2, and the outer edge of each of the enlarged portions is formed with an inwardly directed rail engaging lip 3. From the inner end of the widened or enlarged portions 2 there extends a reduced flat por- 95 tion in the nature of a web 4. The web has an opening 5 therethrough. The web inward of the opening 5 is subjected to a pressure from one of the edges thereof, so that the said web has its said edge forced down- 100 wardly to provide a substantially triangular downwardly inclined wall 7. From the wall 7, the upper edge of the web is pressed for a comparatively long distance at an angle pro- 105 viding a larger triangular surface 9, the lower wall 10 of this surface being rounded inwardly and being extended at a down- 110 ward and outward angle to provide a third triangular surface 11 which is of a size ap- proximately equaling that of the triangular

surfaces 7. In reality, the web is twisted to produce the triangular surfaces 7 and 11, the upper wall of the triangular surface 11 being bent and arranged at an angle, as indicated by the numeral 12, and from thence the web is continued straight and in parallelism with the straight portion end 2. This straight portion is indicated by the numeral 13 and is centrally provided with an opening 14. From the straight portion 13 the web is widened and the said widened portion is bent or otherwise shaped to provide the outer edge thereof with a rail engaging lip 15.

15 When the sections are arranged one over the other, and the lips 3 are disposed at the outer end of the improvement, the angle walls provided by the twisted web will contact. The triangular end walls 7 and 11, at 20 the ends of the central twisted portion of the web serve as abutment walls for preventing the outward movement of one of the sections with respect to the other section. The inner twisted portion, from the center and 25 at the lower edge thereof is partially embedded in the road bed, which, of course, is true with respect to the abutment walls 7 and 11. Through the angle walls 9 of the respective sections, there is passed bolts 16 30 that have their threaded ends engaged by nuts 17. Certain of the bolts 16 may have their heads provided with ring members 18. These ring members 18 may receive therethrough angle ends of rod members 19 which 35 hold the said ties in proper spaced relation to each other. It is, of course, to be understood, that one of the sections is arranged and a rail received thereon before the other section is positioned thereover, and when the 40 sections as thus assembled, spikes or similar retaining means 20 may be passed through the openings 5 in the straight end portions of the webs 4.

The above construction refers to ties designed for use on electric or steam railway systems, and such ties may be also employed in mines or the like, in which instance they are of lighter construction. As a matter of fact, in mines certain of such ties are employed, but in addition thereto, I make use of other ties. The other ties are constructed similar to those previously described, except that the widened end 2' thereof is formed with an extension 21 to one side of 55 the lip 3' thereof, and the said extension 21 is formed with an outwardly projecting plate portion 22. The ties rest on the floor of the mine having their lower edges partly embedded in the said floor, and the said ties 60 are spaced away from each other a distance equaling the distance between the upright braces 23 which support the transverse beams 24 that are in contact with the ceiling of a lead in the mine. The vertical braces 65 23 are arranged over the projecting portions

22 of the tie, and the weight of these braces on the tie holding the latter against movement in any direction.

In connecting the rails in mines ordinary nuts and bolts may be employed for associating the sections of the ties and the spacing means therebetween dispensed with.

Having described the invention, I claim:—

1. A combined tie and clamp for railway rails comprising two similarly constructed 75 metallic members each having an outer flat end formed with a rail engaging lip, said members disposed one on the other to arrange the lips of one of the members opposite the lips of the other member in rail receiving relation, said members, intermediate of the flat ends thereof being twisted, and means connecting the twisted portions of the members.

2. A combined tie and clamp for railway 85 rails comprising two similar members each having flat ends formed with rail engaging lips, and webs between said ends, said members disposed one on the other in contacting relation to arrange the lips of one of the 90 members opposite the lips of the other member in rail receiving relation, and the webs of the members being twisted to provide central triangular shaped portions and end triangular shaped shoulders, and means 95 connecting the webs.

3. A combined tie and clamp for railway rails, comprising two similar members each having its ends provided with rail engaging lips, said members disposed one on the other 100 to arrange the lips of one of the members opposite the lips of the other member in rail receiving relation, integrally formed angularly disposed contacting portions on the members between the lipped ends thereof, 105 means connecting the central portions of the members, said means including rings disposed at the opposite sides of the members, all as and for the purpose set forth.

4. A combined tie and clamp for railway 110 rails, comprising two similar members each having outer flat ends formed with rail engaging lips, each of said members having one of its ends provided with a longitudinal extension disposed laterally of its lip, said 115 members disposed one on the other to arrange the lips of one of the members opposite the lips of the other member in rail receiving relation, said members having reduced portions providing webs between the 120 lipped ends thereof, said webs having spike openings therethrough and having their central portions bent and twisted to provide angularly disposed contacting portions at the center of the webs and angularly disposed contacting shoulders at the ends of the central portions, and means connecting the central portions of the members.

In testimony whereof I affix my signature.
JOHN WILLIAM RYAN.
